REW TROXELL, OF SAN FRANCISCO, CALIFORNIA.

EXPOSURE ATTACHMENT FOR CAMERAS.

1,192,710.

Specification of Letters Patent. Patented July 25, 1916.

Application filed October 6, 1914. Serial No. 865,228.

To all whom it may concern:

Be it known that I, REW TROXELL, a citizen of the United States, residing at San Francisco, in the county of San Francisco and State of California, have invented certain new and useful Improvements in Exposure Attachments for Cameras, of which the following is a specification.

This invention relates to exposure attachments for cameras.

One of the principal objects of the invention is to provide an improved apparatus whereby the shutter of the camera may be conveniently manipulated from a distance, in order that the operator may himself appear in the picture.

Another object of the invention is to provide an improved device of the class specified having an air compressor and electrically operated means for releasing air therefrom at will, and from a distant point, whereby to operate the shutter operating mechanism of a camera.

A further object of the invention is to provide a device of the class described which will be extremely simple, durable, efficient in operation and inexpensive to manufacture.

With these and other objects in view which will become apparent as the description proceeds, the invention resides in the construction, combination and arrangement of parts, hereinafter more fully described and claimed, and illustrated in the accompanying drawing, in which like characters of reference indicate like parts throughout the several figures, of which—

Figure 1 represents a diagrammatical view of the assembled apparatus, showing the same in position ready for operation. Fig. 2 represents a vertical central sectional view through the air compressor. Fig. 3 represents a plan view of the battery case, with the top removed. Fig. 4 represents a vertical transverse sectional view taken on the line 4—4 of Fig. 3.

Referring more particularly to the drawing, 5 indicates an ordinary and well known type of camera shutter operating mechanism, 6 indicates generally the air compressor, and 7 indicates the battery case in which a battery 8 (Fig. 3) is placed. The air compressor is connected by a rubber tube

9 with the shutter operating mechanism, and it contains an electrically operable air release mechanism to be hereinafter described, which may be operated at will at the completion of an electrical circuit through the compressor and battery, and wires 10 connecting them as will be subsequently pointed out.

The air compressor comprises an outer shell or cylinder 11, hermetically sealed at its lower end at 12, and provided at its upper end with a collar 13. The collar is threaded into the upper end of the outer cylinder and is adapted to prevent displacement of the inner cylinder or shell 14 from the outer cylinder. The inner shell 14 is slidable within the outer shell 11 axially thereof, and at its upper end carries the head 15 and at its lower end is hermetically closed by the collar 16. The latter is provided with a threaded opening for receiving the exteriorly threaded sleeve 17. Sleeve 17 carries a peripheral flange 18 exteriorly of the inner shell, and between said flange and collar 16 a leather or other suitable washer 19 is engaged. The washer forms a piston movable with the inner shell 14 and adapted to co-act with the inlet valve mechanism to be described, in attaining the compression of air within the inner shell. Said inlet valve mechanism comprises a valve stem 20 disposed axially within sleeve 17, and projecting at one end through an opening 21 in the inner closed end of the sleeve. The opposite end of the valve stem extends into the central bore of a threaded bushing 22 turned into the interiorly threaded lower end of sleeve 17. The bushing is headed at 23 whereby a fiber or other suitable washer 24 may be compressed against the lower end of sleeve 17 for forming an air-tight joint between said bushing 22 and sleeve. A conical soft rubber or other suitable valve 25 is disposed upon valve stem 20 above the upper beveled end 26 of the bushing, and is adapted to be normally closed against said bushing by action of the coiled spring 27 disposed upon stem 20 between the valve and the closed upper end of sleeve 17.

A conducting socket 28 is carried by head 15, and is insulated therefrom by an insulating sleeve 29. The head is provided

with a recess indicated in dotted lines at 30, and said recess and socket are adapted to receive a plug indicated generally at 31 to which the outer terminals of the wires 10 5 are connected. Head 15 is provided with an exteriorly threaded depending annular flange 32, which carries at its lower end a collar 33. The collar 33 is secured to the flange and in turn supports an electromagnet 34. One terminal of the wiring of the latter is grounded at 35 to the core 36 of the magnet, while the other terminal 37 of said wire is conducted through an insulator 38 into an opening 39 provided in the sleeve 33 10 at one side thereof. Terminal 37 of the wire is connected by means of a brass sheet or strip 40 to which it is soldered, with the inner end of the socket 28 at 41. An insulating sheet 42 is disposed between brass strip 40 and the depending flange 32. The upper end of core 36 is axially bored, and contains a coiled spring 43. The latter engages a spring guide 44 at its upper end, said guide being slidable within the bore. The 15 guide is provided with a socket for receiving the lower end of the outlet valve stem 45. The latter extends through and is secured to the armature 46 of the magnet, and on the opposite side of the armature from said magnet carries a conical soft rubber valve 47. The latter is adapted to control the exit of air through the opening 48 connecting the interior of the inner shell with a passage 49 drilled radially into the head 15 from one 20 side thereof. The outer end of passage 49 is enlarged and threaded at 50 for receiving the nozzle 51 (Fig. 1) to which one end of tube 9 is connected.

The battery case comprises a rectangular body portion 52 closed on one side by a bottom 53 which at its edges is extended beyond and overhangs the body portion at 54. A top 55 is provided having an inner flange 56 adapted to engage within the body 52 for 25 providing a tight joint, said top being extended at its edges to provide the overhanging flanges 57. When the apparatus is not in use the flanges together with the body portion form a holder upon which the wiring 30 10 may be conveniently wound.

A metallic spring detent or leaf switch 58 is disposed upon and secured to bottom 53 near one end of the holder, said switch being insulated from the bottom at 59. A metallic terminal 60 is disposed upon the switch near one end and insulating therefrom at 61. One pole 62 of the battery 8 engages the terminal 60 while the battery is in position, and the other pole 63 of said battery is disposed in such relation to the switch 58 that depression of the latter will cause a contact 60 between the switch and pole 63. A button 64 carried by the switch 58 projects through

and is insulated from the bottom 53, whereby the switch may be readily manipulated by 65 the operator. The wires are provided with insulation throughout their length except at their terminals where they are connected respectively with the plug and with the switch 58 and contact 60. 70

Upon depression of switch 58 an electrical circuit will be established through pole 63 of the battery, switch 58, one of the wires 10, socket 28, brass strip 40, thence through the magnet winding, through the core of the 75 magnet, shell 34 thereof, sleeve 33, flange 32, head 15, through the other wire, and thence back through contact 60 and pole 62 to the battery.

The operation of the device may be briefly 80 described as follows: The inner and outer shells 14 and 11 respectively, are separated as far as possible relatively to each other, and when in this position an opening 65 in the outer shell 11 near the upper end thereof 85 is uncovered by the piston, so that air and atmospheric pressure is admitted into the outer cylinder 11. The cylinders are then compressed until the piston passes opening 65 on its inward stroke, and further movement of the cylinders compresses the air within the outer shell, hence opening valve 25 against the tension of spring 27, allowing the escape of compressed air from the outer into the inner cylinder 14. At the end of 90 95 the inward stroke the valve 25 closes by action of spring 27, thus preventing escape of the compressed air at this point. The opening 39 in collar 33 allows the passage of the compressed air around the electromagnet 100 and into the upper end of the inner shell. Energization of the electromagnet at the will of the operator by completion of the circuit described, will cause the movement of armature 46 toward the magnet, and against 105 the action of spring 43, thus opening the outlet valve 47 and allowing escape of air through the passage 49, and tube 9 whereby to operate the shutter mechanism 5. The impulse given the armature may be instantaneous or for an extended period, according to whether the circuit is closed for a short or a long time, and thus either instantaneous or time exposures may be made.

Upon opening the circuit by the release of 110 switch 58 spring 43 will instantly reclose valve 47 to cut off the flow of air. 115

Although I have described the preferred embodiment of my invention, I may desire to make such changes in the construction, 120 combination and arrangement of parts thereof as do not depart from the spirit of the invention and the scope of the appended claims.

I claim:

1. In an apparatus of the class described,

an outer shell, an inner shell adapted to telescope within the outer shell, a piston carried by the inner shell, an inlet valve carried by the piston to allow the entrance of compressed air into the inner shell upon relative closing movement of said shells, an outlet valve adapted to control the exit of compressed air from the inner shell, and electrically operable means for controlling said outlet valve.

2. In an apparatus of the class described, an outer shell, an inner shell telescopically supported in the outer shell, means for allowing the entrance of compressed air from the outer to the inner shell as the shells are closed relatively to each other, an outlet valve adapted to control the exit of compressed air from the inner shell, an electromagnet supported by the inner shell, said magnet having its core provided with a bore at one end, a spring disposed within the bored end of the core, a spring guide within the said bored end, a valve stem supported at one end by the stem guide, said outlet valve being carried by said valve stem, a magnet armature carried by said valve stem, and means for energizing the magnet at will.

3. In a device of the class described, the combination of an inner shell, means for compressing air therein, an outlet valve for controlling the exit of compressed air from the inner shell, an electromagnet carried by the inner shell and adapted to control said outlet valve, a battery, means for carrying the same independently of the inner shell, a conducting socket carried by the inner shell, an electrical conductor between said socket and one end of the magnet winding, the opposite end of said winding being grounded in the magnet core, and means for establishing an electrical circuit through the magnet for controlling the outlet valve.

4. In a device of the class described, an inner shell, a head, a depending flange provided on said head and threaded within said shell at one end thereof, a piston carried at the opposite end of the shell, an inlet valve carried by the piston, means adapted to contact with said inner shell for forcing compressed air therein through said inlet valve, a sleeve carried by said depending flange, an electromagnet supported by said sleeve, an outlet vent formed in said head, said sleeve provided with an opening for forming communication between said inner shell and outlet vent, a valve for controlling the passage through said vent, an armature for the magnet, said valve being operable by movement of the armature, and means for energizing said magnet at will.

5. A device of the class described comprising an inner shell, means for compress-

ing air therein, an outlet valve adapted to control the exit of air from said inner shell, 65 an electromagnet adapted to control the operation of said valve, a head for said inner shell, a flange carried by said head and extending within said shell, a sleeve supported by the flange, said electromagnet being supported by said sleeve, said sleeve provided at one side with an opening therein, a conducting plug carried by and insulated from said head, a conducting strip connected at one end with said plug and extended at its 75 opposite end into the opening in said sleeve, one end of the magnet winding being connected to said opposite end of the conducting strip, an insulator disposed between said strip and said flange, the opposite end of 80 said magnet being in electrical communication with said head, a battery, and means for throwing the magnet into electrical circuit with the battery.

6. An apparatus of the class described 85 comprising an outer shell, an inner shell telescoping therein and adapted when moved relatively to the outer shell, to compress air within the outer shell, an inlet valve controlling admission of compressed air to the 90 inner shell, an outlet valve carried by the inner shell controlling the exit of compressed air from the inner shell, and electrically operable means for controlling said outlet valve.

7. An apparatus of the class described comprising an inner shell having a head at one end thereof, and having an inlet valve at the opposite end thereof, means for forcing compressed air through said inlet valve 100 into said shell, an exit vent provided in the head, an electromagnet supported within the inner shell, a valve operable by said magnet for controlling the passage through said exit opening, means for allowing passage of air from the inner shell around said electromagnet to the exit opening, and means for controlling said magnet.

8. An apparatus of the class described comprising an outer shell, an inner shell 110 telescoping therein and adapted when moved relatively to the outer shell, to compress air within the outer shell, an inlet valve controlling admission of compressed air to the inner shell, an outlet valve carried by the inner shell controlling the exit of compressed air therefrom, a tube connecting the outlet valve with the shutter mechanism of a camera, and electrically operable means for controlling said outlet 115 valve.

9. An apparatus of the class described comprising an outer shell, an inner shell telescoping therein and adapted when moved relatively to the outer shell, to compress air within the outer shell, an inlet

valve controlling admission of compressed air to the inner shell, an outlet valve carried by the inner shell controlling the exit of compressed air therefrom, a tube communicating with the outlet valve and with the shutter mechanism of a camera, an electrically operable means for controlling the action of the outlet valve, a holder, a bat-

tery carried thereby, and means for establishing electrical communication between 10 said battery and valve controlling means.
